CLAIM

The ornamental design for an electronic vaping device, as shown and described.

DESCRIPTION

FIG. 1 is an isometric view of the top, front, and right side of a first embodiment of an electronic vaping device.

FIG. 2 is an isometric view of the bottom, rear, and right side of the electronic vaping device depicted in FIG. 1.

FIG. 3 is a top plan view of the electronic vaping device depicted in FIG. 1.

FIG. 4 is a bottom plan view of the electronic vaping device depicted in FIG. 1.

FIG. 5 is a right side elevational view of the electronic vaping device depicted in FIG. 1, the left side elevational view being a mirror image thereof.

FIG. 6 is a rear elevational view of the electronic vaping device depicted in FIG. 1.

FIG. 7 is a front elevational view of the electronic vaping device depicted in FIG. 1.

FIG. 8 is an isometric view of the top, front, and right side of a second embodiment of an electronic vaping device, which is similar to the embodiment of FIG. 1.

FIG. 9 is an isometric view of the bottom, rear, and right side of the electronic vaping device depicted in FIG. 8.

FIG. 10 is a top plan view of the electronic vaping device depicted in FIG. 8.

FIG. 11 is a bottom plan view of the electronic vaping device depicted in FIG. 8.

FIG. 12 is a right side elevational view of the electronic vaping device depicted in FIG. 8, the left side elevational view being a mirror image thereof.

FIG. 13 is a rear elevational view of the electronic vaping device depicted in FIG. 8.

FIG. 14 is a front elevational view of the electronic vaping device depicted in FIG. 8.

FIG. 15 is an isometric view of the top, front, and right side of a third embodiment of an electronic vaping device, which is similar to the embodiment of FIG. 1, but wherein the cross-hatching represents the color blue.

FIG. 16 is an isometric view of the bottom, rear, and right side of the electronic vaping device depicted in FIG. 15.

FIG. 17 is a top plan view of the electronic vaping device depicted in FIG. 15.

FIG. 18 is a bottom plan view of the electronic vaping device depicted in FIG. 15.

FIG. 19 is a right side elevational view of the electronic vaping device depicted in FIG. 15, the left side elevational view being a mirror image thereof.

FIG. 20 is a rear elevational view of the electronic vaping device depicted in FIG. 15.

FIG. 21 is a front elevational view of the electronic vaping device depicted in FIG. 15.

FIG. 22 is an isometric view of the top, front, and right side of a fourth embodiment of an electronic vaping device, which is similar to the embodiment of FIG. 15.

FIG. 23 is an isometric view of the bottom, rear, and right side of the electronic vaping device depicted in FIG. 22.

FIG. 24 is a top plan view of the electronic vaping device depicted in FIG. 22.

FIG. 25 is a bottom plan view of the electronic vaping device depicted in FIG. 22.

FIG. 26 is a right side elevational view of the electronic vaping device depicted in FIG. 22, the left side elevational view being a mirror image thereof.

FIG. 27 is a rear elevational view of the electronic vaping device depicted in FIG. 22; and,

FIG. 28 is a front elevational view of the electronic vaping device depicted in FIG. 22.

The electronic vaping device is shown with a symbolic break in its length. The appearance of any portion of the article between the break lines forms no part of the claimed design.
